UNITED STATES PATENT OFFICE.

JULIUS JACOB CZEPUHL, OF LANCASTER, PENNSYLVANIA, ASSIGNOR OF
ONE-HALF TO EMIL MEYER, OF SAME PLACE.

ELECTRIC SIGNALING BETWEEN RAILWAY-TRAINS.

SPECIFICATION forming part of Letters Patent No. 515,145, dated February 20, 1894.

Application filed August 8, 1893. Serial No. 482,662. (No model.)

To all whom it may concern:

Be it known that I, JULIUS JACOB CZEPUHL, a subject of the Emperor of Germany, residing in Lancaster, in the county of Lancaster 5 and State of Pennsylvania, have invented certain Improvements in Electric Signaling between Railway-Trains, of which the following is a specification.

This invention relates to improvements in 10 electric railway signals; and the object of the invention is to enable locomotives to signal their approach to each other.

The invention consists in the construction and combination of the various parts, as hereinafter fully described, and then specifically 15 pointed out in the claims.

I attain my object by the mechanism illustrated in the accompanying drawings, in which—

20 Figure 1 is a side view of a locomotive having the signaling apparatus attached thereto, portions of the cab and boiler being cut away to fully show the same. Fig. 2 is a top plan view of the rails of the track, the electrical 25 and signaling apparatus, and the wheels of the locomotive connected therewith. Fig. 3 is an enlarged side view of the throttle-lever and the device connected therewith for opening and closing the electric circuit, and Fig. 30 4 a top view of said device taken on the line $x-x$ of Fig. 3. Fig. 5 is a front elevation of 35 a pair of driving-wheels and their axle, showing a device for separating them electrically. Similar letters indicate like parts throughout the several views.

Referring to the details of the drawings, A indicates the rails of a railway track, the adjacent ends of those of each line being united by wires A', forming electrical connection between them.

B is a circuit rail (so called for the purposes of this specification), and is located midway between the track rails.

Beneath the rear of the cab C there is a 45 wheel D, attached thereto by a hanger D', and which engages and travels over circuit rail B. A contact plate d is bolted to hanger D' and bears against wheel D.

Beneath one of the seats of the cab there is 50 placed an electric battery E, one pole of which is connected with contact-plate d by a wire e

and the other by a wire e' with a contact pin f, passing through one end of a horizontal bar F, formed of any suitable non-conducting material and supported above the floor of the cab 55 by legs f'. A contact-pin f², passing through the other end of bar F, is connected with one part of an alarm G, secured to the front of the cab, by a wire g, and the other part of said alarm is connected by a wire g' with the upper ends of wires g², the lower ends of which are attached to contact-plates H, secured to opposite sides of the engine and having their free ends bearing against the rear driving-wheels W.

I indicates a throttle-lever having attached thereto a contact-bar L, located opposite to and parallel with bar F. Contact-bar L is moved to and fro with said lever in opening and closing the throttle. Through contact-bar L there are 60 perforations l, of greater diameter than contact-pins f and f², projecting from bar F and having attached thereto, respectively, connecting-wires e' and g. As said lever moves contact-bar L the side of said contact-bar slides on 65 or against the ends of pins f and f² and is in contact therewith while said lever holds the throttle open, thus closing the end of the circuit in the engine. But when said lever is in the position it occupies when the throttle is 70 closed, perforations l register with pins f and f², as shown in Fig. 4 and the connection between said pins and the contact-bar is broken and the circuit is broken. That the circuit 75 may be closed when perforations l are opposite contact pins f and f², there is attached to the outer side of contact-bar L a key formed of any suitable material and comprising a jointed lever M, having the sections fulcrumed in lugs m, a handle or thumb button M' at 80 the end of one of the sections, a spring m' between said button and the face of contact-bar L, and contact-pins m² on the inner faces of the lever sections engaging perforations l and having their free ends normally held back 85 within the inner face of said contact bar. As will be seen, the joint between the lever-sections is such that pressure on the thumb-button causes both pins m² to engage the contact-pins f and f², when said contact pins 90 register with perforations l, as shown by dotted lines in Fig. 4, thus closing that end of

the circuit. Lugs *m* and the face of contact-bar *L* adjacent to the jointed lever are formed of any non-conducting material. If desirable, when two locomotives are electrically connected, telegraphic signals may be exchanged by means of the key.

In Fig. 5 is shown a device for electrically separating the driving-wheels *W*. The axle *V* is divided in the center and on the contiguous ends thereof are formed annular flanges *R*, between which is interposed a plate, *r*, of any suitable non-conducting material, said flanges and the plate *r* being properly secured by bolts *t*. The device just described must be attached to the different locomotives, as a complete circuit can alone be formed by closing the ends of the circuits in the two locomotives on the same track or on two tracks connected by a closed switch. One pole of each battery is connected with both track rails to insure a circuit with each locomotive going in either direction. Circuit rail *B* is divided into convenient sections separated by an interval *b*, as shown in Fig. 2 of sufficient width to completely break electrical connection between them. These sections are formed similarly to the divisions of a road by the block system, and the intervals between them are generally placed opposite the signal towers of the road, so that should a locomotive be accidentally allowed to pass onto a section or block still occupied by another train the electrical alarms would at once apprise the engineers of both locomotives of the fact. The intervals are also formed at opposite sides of switches, the opening and closing of the switch forming a break in or closing of the circuit rail.

I do not limit myself to the particular arrangement or location of parts herein shown and described, as many changes may be made therein without departing from the spirit of my invention.

Having thus described my invention, what I claim as new, and desire to secure by Letters Patent, is—

1. In an electric-signal, the combination, with a bar having contact-pins in opposite ends thereof, of electrical conductors connected with said pins, a movable contact-bar constructed to bear against said contact-pins, said contact-bar having perforations adapted to register with the contact-pins, and a key secured to the contact-bar and having pins entering said perforations and adapted to be

simultaneously engaged with said contact-pins when said perforations register therewith, substantially as and for the purpose specified.

2. In an electric signal, the combination, with a track having a circuit rail, of a locomotive having a contact wheel engaging the circuit rail, a bar having contact-pins in opposite ends thereof, a battery connected with the contact-wheel and one of the contact-pins in said bar, a connection between the other contact-pin of said bar and an alarm, a connection between the alarm and a track-rail, and a contact-bar secured to the throttle-lever and constructed to bear against said contact pins, said contact-bar having perforations adapted to register with the contact-pins when the throttle is closed, substantially as and for the purpose specified.

3. In an electric signal, the combination, with a track having a circuit rail, of a locomotive having a contact-wheel engaging the circuit rail, a bar having contact-pins in opposite ends thereof, a battery connected with the contact-wheel and one of the contact-pins in said bar, a connection between the other contact pin of said bar and an alarm, a connection between the alarm and a track rail, and a key fulerumed opposite said bar and having pins adapted to be simultaneously engaged with said contact-pins, substantially as and for the purpose specified.

4. In an electric signal, the combination, with a track having a circuit rail, of a locomotive having a contact-wheel engaging the circuit rail, a bar having contact-pins in opposite ends thereof, a battery connected with the contact-wheel and one of the contact-pins in said bar, a connection between the other contact-pin of said bar and an alarm, a connection between the alarm and a track rail, a contact-bar secured to the throttle lever and constructed to bear against said contact-pins, said contact-bar having perforations adapted to register with the contact-pins when the throttle is closed, and a key secured to the contact-bar and having pins entering said perforations and adapted to be engaged with said contact-pins when the same register with the perforations, substantially as and for the purpose specified.

JULIUS JACOB CZEPUHL.
